CLAIM

The ornamental design for a combined ceiling fan housing, light kit and fan blade bracket, as shown and described.

DESCRIPTION

FIG. 1 is a perspective view of the present design;
FIG. 2 is a front view of the present design;
FIG. 3 is a rear view of the present design;
FIG. 4 is a left side view of the present design;
FIG. 5 is a right side view of the present design;
FIG. 6 is a top view of the present design; and,
FIG. 7 is a bottom view of the present design. ps The broken
lines in the drawings depict parts of the combined ceiling fan
housing, light kit, and fan blade bracket that form no part of
the claimed design.
